UNITED STATES PATENT OFFICE.

MATT Q. CORBETT, OF DAYTON, OHIO.

AIRSHIP MOORING MAST.

Application filed April 24, 1925. Serial No. 25,636.

This invention relates to an airship mooring mast for rigid, non-rigid, or semi-rigid airships and the like.

One of the principal objects of the invention consists in providing a mast to which the airship is secured at or about its center of resistance, for the purpose of reducing the movement of a moored ship to the minimum.

Another important object consists in the provision of a swing or cradle type mooring mast, which allows the whole ship freedom to roll, pull or surge ahead with respect to the mast, and especially advantageous in this connection is the provision of weights suspended from the swing or cradle, which serve to dampen the movements of the moored ship gradually as distinguished from positively and non-yieldingly, as is ordinarily the case.

A further object of the invention is to provide a rotatable mooring mast having lateral extensions connected preferably with the ship's car on opposite sides of the ship, whereby rotation is communicated to the mast as the moored ship shifts in the wind.

Still another object of the invention consists in the provision of a mast of the character described which has rollers removably mounted on the base thereof, to serve in the rotation of the mast as a whole in the shifting of the moored ship. The wheels are removable so that any two oppositely disposed wheels may be left on the mast when the others are removed, to permit the transporting of the mast from place to place. Whenever the mast is to be used, a foot bearing is fixed in the ground on which the mast is arranged to rotate, and any wheels which have been removed are replaced.

The foregoing and other objects of the invention are brought out in the following specification, wherein reference is made to the accompanying drawings illustrating the invention.

Fig. 1 is a front view of a mooring mast constructed in accordance with the invention, having an airship of the dirigible type moored thereto.

Fig. 2 is a side view of Fig. 1, and

Fig. 3 is an enlarged fragmentary detail showing the arrangement of mooring plugs provided on the ship.

Fig. 4 is a plan view of the base of the mooring mast.

Fig. 5 is a plan view particularly in section showing the gripper member of the mooring mast.

The mast comprises a base 10 arranged to rotate on a central foot bearing 11, anchored by stakes 12 into the ground wherever the mast is stationed. The base consists of criss-crossed bars 13 secured at their common intersection to the foot bearing 11, and having an upright center post 14, to which sloping truss bars 15 are attached similarly to the bars 13, and extended from the top of the post 14 to the outer extremities of the bars 13. The entire base is universally tiltable on the bearing 11 as the latter is of a self aligning and adjustable character. This is to accommodate the rocking of the base in the movement of the wheels 16 over uneven ground. The wheels 16 are attached to the outer ends of the bars 13 by any suitable form of detachable connection indicated at 17. It will be seen that the wheels provide easy turning movement for the mast in the shifting of the moored ship, and when one or two of the wheels are removed leaving at least two wheels in place on opposite sides of the mast, portability is afforded when the mast is detached from its central bearing, and is to be transported to some other place on the field.

The base 10 supports a vertical V frame consisting of two oppositely inclined spars 18 connected at their lower ends to the top of the central post 14. The spars 18 have a swing cable 19 strung therebetween, the cable 19 having sufficient slack between the spars to permit of from eight to ten feet of free motion of the ship in rolling, pulling and surging when moored. The cable preferably extends down from the ends of the spars 18 for connection with the base 10 at the outer extremities of the bars 13. The spars 18 are braced by guy wires 20 and 21 extending between the spars 18 and the outer ends of the bars 13 on four sides of the mooring mast. There are also criss-crossed wires 22 and 23 extending between the spars 18 below the swing cable 19 and attached to the spars 18, suitably at common points with the wires 20 and 21. The spars 18 diverge sufficiently so their free ends extend out laterally an appreciable distance on opposite sides of the moored ship 24, and afford moment arms to communicate rotation to the mooring mast in the shifting of the ship in the wind. The ship's car 25 has halyards 26 detachably connected therewith which extend from the extremities of the spars 18 on opposite sides of the ship. These halyards are connected to the car when the ship is moored and may be

released from the car by a person therein, preparatory to taking off. In a cross wind, the force of the wind tending to shift the ship to head into the wind will communicate 5 a pull on either of the halyards 26, to rotate the mooring mast coincident with the shifting of the ship. Thus any possible injury to the envelope of the ship by contact with one of the spars is positively prevented, and one 10 of the gravest dangers incident to the mooring of a ship of this character is avoided.

The ship 24 has a pair of mooring plugs 27 and 28 strung from cables 29 at the bow on the underside of the hull, at a point determined 15 as the center of resistance of the ship and its car. In heading into the wind the ship is maintained on an even keel since wind forces on both sides of the point of attachment of the ship to the mast are substantially evenly balanced. The violent pitching and surging ordinarily experienced in a heavy wind is practically entirely dispensed with by virtue of this method of mooring. There is no likelihood of the ship tearing 20 loose from its mooring, since all of the loads on the mooring are even and can be more or less accurately anticipated.

The mooring plugs 27 and 28 are arranged for separate engagement in a grip fitting 30 provided at the middle of the swing cable 19. The grip fitting may be of any well known form, as shown in Fig. 5, capable of quick 30 release through the medium of a line 31, extended from the grip fitting down to the ground. One of the plugs, as 27, is always under the control of persons in the car 25 by a landing line 32 attached to the bottom of the plug 27, and extending back to the car 25 as shown in Fig. 2. The other plug 28 is 35 engaged in the grip fitting 30 into which it is entered on the mooring of the ship. The program on landing is to drop the landing line to which a line threaded through the grip fitting by a ground man is attached. The 40 ground men then draw in on the line until the plug is secured in the grip fitting. In the illustration in Fig. 1 the line 33 has served this purpose. It is connected by a quickly 45 releasable ring with the mooring plug and is detached from the plug after the mooring of the ship preparatory to taking off. The thought is to enable taking off without the assistance of ground men, and this is accomplished merely by stringing the line 31 back 50 to the car 25 at which point it may be pulled by a person in the car on taking off. Precautions are always taken to have one of the 55 plugs connected by a landing line to the car. In the illustration while the plug 28 served in 60 the particular instance shown for mooring the ship, the plug 27 will serve the next time, at which time the landing line 32 will be dropped and the procedure followed as above outlined, in threading the plug 27 into the grip fitting.

65 At that time the plug 28 will have a landing

line attached thereto and strung back to the car 25.

The swing cable 19 affords freedom of movement in the rolling, pulling and surging of the moored ship. In order to avoid the 70 possibility of injury to the envelope of the ship, a pair of pneumatic buffer balls 34 are mounted rotatably on the cable 19 on opposite sides of the grip fitting 30. These balls are free to turn as the ship rides onto and off 75 the mast and prevent the engagement of the hull with either the cable or the grip fitting. The freedom of motion afforded by the swing cable is gradually restrained by the suspension of weights 35 on a cable 36, suitably attached to the grip fitting 30. Inasmuch as 80 this is at the mid point of the cable, it is apparent that the initial movement of the moored ship from normal is less restrained than is the case when the ship approaches 85 more and more the maximum point to which it is capable of movement with respect to the mast. This is due to the fact that the weights have a greater moment arm the farther the swing cable is moved from a position of normal suspension. This method of dampening 90 the movements of the moored ship has been found to be of decided advantage over the old method of positive mooring and avoids 95 the danger of a ship tearing loose from its mooring as there are no sudden and unprecedented loads on the mooring cables.

I claim:

1. A mooring mast for airships comprising a support, a swing therein, means for attaching an airship thereto, and buffer means rotatably mounted on said swing to cushion the ship's hull on said swing from movement relative thereto.

2. A mooring mast for airships comprising a support, a swing therein having means for attaching an airship thereto, means to cushion the ship's hull from movement relative to said swing, and means suspended from the middle of said swing serving to restrain the movement of the ship by slackening the movement of said swing.

3. In combination, a rotatable V frame, a swing suspended therein having means for detachably securing an airship and connections from the sides of said ship to the sides of said V frame to communicate a turning movement thereto, in the shifting of the moored ship.

4. In combination, a rotatable mooring mast provided with a pair of spaced uprights, a swing cable attached thereto, means for detachably securing an airship cable, means contacting with the airship at spaced points on both sides of the vertical axis of said airship providing a moment arm to turn said mast, and a connection from a point on said ship intermediate its ends to said means, for communicating rotation to the mast in the shifting of the moored ship.

5. In combination, a mooring mast, an airship to be moored thereto, a grip fitting on the mast, a pair of mooring plugs either of which is adapted for engagement with said grip fitting, one of said mooring plugs having a landing line leading always to the ship's car when the other plug is engaged with the grip fitting and vice versa.
6. In combination, a mooring mast comprising a swing support, a grip fitting in the middle of said swing, an airship having a plug to be engaged in said grip fitting, and dampening weights suspended from said grip fitting.
- 10 7. In a portable airship mooring mast, the combination of a base, rollers on said base, and a V frame mounted on said base having a slack cable swing fixed at its ends to the spaced ends of the V frame for mooring an airship therein, and connections from the opposite sides of the ship to the swing to communicate rotation to the mooring mast in the shifting of the moored ship.
- 15 8. In a mooring mast the combination of a swing support, a pair of buffer rollers serving as a cushion between the swing support and the hull of an airship moored thereto, and a grip fitting between said rollers to receive a plug of said airship for mooring the latter.
- 20 9. In a mooring mast the combination of a swing support, a pair of buffer rollers serving as a cushion between the swing support and the hull of an airship moored thereto, a grip fitting between said rollers to receive a plug of said airship for mooring the latter, and counter-weights suspended from said grip fitting for dampening the movement of the moored ship.
- 25 10. In an airship mooring mast a base comprising criss-cross members arranged to be 40 rotatably mounted on a central bearing, and wheels mounted on the outer ends of said criss-cross members to permit rotation of said mast on said bearing, said wheels being removable one or more at a time, leaving at least two diametrically opposed wheels to serve as carriers for the frame to afford portability.
- 30 11. In an airship mooring mast, the combination with an airship and means for mooring the same, rotatable pneumatic buffer 50 means for cushioning any impact of the ship with the mast.
- 35 12. In an airship mooring mast, the combination with an airship and means for mooring the same, rotatably mounted buffer balls 55 on said mast for cushioning any impact of the ship with the mast, while permitting movement with respect thereto.
- 40 13. A portable mooring mast for lighter-than-air craft comprising a unitary movable support, a swing therein, buffer means rotatably and centrally mounted on said swing providing a cushion for said craft and means interconnecting said buffer means serving to attach said craft to said swing. 60 65
- 45 14. A portable mooring mast for aircraft comprising a rotatable tubular cone-shaped support, a swing therein having means for attaching an airship thereto at its center of resistance, means to cushion the ship's hull from movement relative to said swing and means suspended from said attaching means to gradually restrain the movement of the ship by resisting the movement of the swing. 70

In testimony whereof I affix my signature.
MATT Q. CORBETT.
